DESIGN FOR A TOY ROCKING HORSE

Benjamin J. Compagnoni and Victor Compagnoni, Detroit, Mich.

Application September 7, 1939, Serial No. 87,080

Term of patent 7 years

To all whom it may concern:

Be it known that we, Benjamin J. Compagnoni and Victor Compagnoni, the former a citizen of Italy and the latter a citizen of the United States of America, both residing at Detroit, in the county of Wayne and State of Michigan, have jointly invented a new, original, and ornamental Design for a Toy Rocking Horse, of which the following is a specification, reference being had to the accompanying drawings, forming part thereof.

With reference to the drawings:

Figure 1 is a side elevation of the toy rocking horse showing our new design; Figure 2 is a top plan view, and Figure 3 is a front elevation thereof.

We claim:

The ornamental design for a toy rocking horse, as shown.

BEN. J. COMPAGNONI.
VICTOR COMPAGNONI.
